UNITED STATES PATENT OFFICE.

JAMES P. FINERTY, OF DUNMORE, AND FRANCIS CROGHAN, OF SCRANTON, PENNSYLVANIA.

REMOVABLE BRASS FOR LOCOMOTIVE-BOXINGS AND LOCKING MEANS THEREFOR.

1,358,306.

Specification of Letters Patent. Patented Nov. 9, 1920.

Application filed November 6, 1919. Serial No. 336,087.

To all whom it may concern:

Be it known that we, JAMES P. FINERTY and FRANCIS CROGHAN, citizens of the United States, residing at Dunmore and 5 Scranton, respectively, in the county of Lackawanna, State of Pennsylvania, have invented a new and useful Removable Brass for Locomotive-Boxings and Locking Means Therefor; and we do hereby declare the following to be a full, clear, and exact description 10 of the invention, such as will enable others skilled in the art to which it appertains to make and use the same.

The invention relates to removable brasses 15 for locomotive boxings and locking means therefor, and has for its object to provide a removable brass, which brass may be easily and quickly placed within the boxing and locked in place therein, by means of 20 segmentally shaped locking rings having their peripheral edges disposed in a channel eccentric to the axis of the axle and consequently eccentric to the concave bearing surface of the brass. The thickness of the 25 abutting ends of the segmental locking rings being greater than the horizontal width of said locking rings at their ends which are disposed substantially in alignment with the axis of the axle, thereby 30 forming means whereby as the axle revolves any tendency to rotate with the axle will be prevented by the jamming action of the narrow portions of the crown brass and the segmental sections of the liner, this 35 for the reason that the width of the segmental liner sections and the lower ends of the brass increase and taper to their maximum width at their upper sides.

The present practice is to cast crown 40 brasses with flanges then drill holes through said flanges after placing the liner or crown brass within the boxing, in which holes a multiplicity of bolts are threaded. After the crown brass is so secured within the 45 boxing its bearing surface is machined and the boxing again placed on the engine. It has been found that to renew a crown brass of this type the time required would amount to anywhere from one to two hours per liner, 50 and when it is considered that there are as many liners or boxings as driving wheels on engines, some engines having four, there being as many as sixteen in some engines,

it will be seen that if an engine has sixteen bearings that engine would be laid up 55 and out of service thirty-two hours. Also under the present practice considerable material is consumed, for the reason that the crown brass and liner where the same are cast together are poured under what is 60 known as the poured system, and after the same are poured integrally with each other it is necessary to machine the same to form bearing surfaces thereon. When pouring or when casting the crown brass and the 65 liner together in one piece it has been found that a considerable cut is necessary to be taken, from the bearing surfaces thereof for the reason that the castings for a considerable depth are faulty and have flaws 70 incident to casting. In those forms wherein the liners are cast and bolted on the boxing by many bolts the present invention eliminates the necessity of boring, threading, or tapping, many holes and counter- 75 sinking said holes for the reception of numerous bolts. Therefore the present invention saves the cost of bolts, the present practice of redrilling the holes and remaching bolts, also the drilling and counter- 80 sinking of the liner which is necessary where liners are being replaced with new liners.

A further object is to provide a crown brass for the boxing, which crown brass is 85 segmentally shaped and has its outer face eccentric to its concave face, said crown brass being pressed into the boxing and into segmentally shaped members forming a liner. The segmentally shaped members forming the liner are disposed in an arcuate beveled channel of the boxing, which beveled channel is eccentric to the center of the crown brass bearing, eccentric to the outer periphery of the crown brass and eccentric to the axis of the axle. 90

With the above and other objects in view the invention resides in the combination and arrangement of parts as hereinafter set forth, shown in the drawings, described and claimed, it being understood that changes 95 in the precise embodiment of the invention may be made within the scope of what is claimed without departing from the spirit of the invention.

In the drawings:—

Figure 1 is a front elevation of a con-

105

ventional form of boxing showing the improved crown brass and locked liner applied thereto.

Fig. 2 is a vertical sectional view taken on line 2—2 of Fig. 1.

Fig. 3 is a side elevation of one of the segmental sections of the liner, showing its beveled flange for engaging a beveled channel in the face of the boxing.

- 10 Referring to the drawings, the numeral 1 designates the conventional form of engine boxing and 2 a liner carried in one face of the boxing 1. The liner 2 comprises segmental sections 2^a and 2^b, which sections 15 have their ends 2^c in abutting engagement with each other thereby forming a semi-circular liner having its side end open so that an axle may be received within the arch of the boxing and within the liner.
- 20 The ends 2^c of the segmental sections 2^a and 2^b are wider than the ends 2^d, the purpose of which will presently appear. Liner 2 as a whole has a beveled engagement with a bevel channel 3 on the outer face of the boxing, the radius of said channel being indicated by the radius line *d* shown in Fig. 1. The segmental sections 2^a and 2^b of the liner are provided with apertures 5, through which apertures pins may be placed which 30 pins would engage hoies in the boxing so that the liner as a whole may be held in position while the same is being machined. The inner periphery of the segmental sections 2^a and 2^b are eccentric to the radius *d* and are concentric with the radius *c* as indicated in Fig. 1, therefore it will be seen that when the crown brass 4 is pressed longitudinally into the boxing, the flange 5^a thereof will engage the inner periphery of the liner sections 2^a and 2^b, said crown brass will be 40 prevented from longitudinal movement in the direction of the arrow *e*, Fig. 2, by means of the flange 5^a engaging the marginal edge 6 of the arch of the boxing. Crown brass is forced into position under considerable pressure so that the same will be securely held therein and prevented from working loose. The lower ends or edges of the crown brass 4 engage shoulders 7, which 45 extend transversely through the arch of the boxing, therefore it will be seen that the crown brass is securely held within the arch of said boxing. After the crown brass has 50 been forced into position and the liner as a whole securely held in position by said crown brass the inner periphery of the crown brass is machined to the proper diameter as indicated by the radius line *a* shown

in Fig. 1. The crown brass having been machined the boxing as a whole is then 60 ready to be replaced on an engine. When it is necessary to remove the liner sections 2^a and 2^b, all that is necessary to be done is for the boxing to be removed from the engine and off of the axle 8, after which 65 pressure is applied to the end 9 of the crown brass and the brass forced outwardly from the arch of the boxing in the direction of the arrow *f*. After the crown brass has been forced out of the boxing it will be seen that 70 the segmental sections 2^a and 2^b which form the liner 2 will drop out of position within the bevel channel 3. It will be seen that it will only require a few minutes to press the crown brass out of the boxing and allow the 75 sections of the liner 2 to drop out of the bevel channel 3 in the face of the boxing. This operation in the conventional form of 80 crown brass and liners now in use would require at least an hour's time.

The invention having been set forth what is claimed as new and useful is:—

1. The combination with an engine boxing having an arch therein, of a crown brass disposed in the upper end of said arch, the outer periphery of said crown brass being provided with a flange for limiting the inward movement of the same when pressed into place, a liner ring formed in sections and disposed in a recess in the face 90 of the boxing, the radius of the inner periphery of the liner being eccentric to the radius of the inner periphery of the crown brass and in engagement with the crown brass flange, the outer periphery of the liner being eccentric to the outer periphery of the crown brass flange, said liner being entirely maintained and held in the recess by means of the crown brass flange.

2. The combination with a boxing having 100 an arch therein, of a crown brass disposed in the upper end of said arch, an arcuate recess in the boxing adjacent the upper end of the arch, a sectional liner disposed in said recess and engaged by the crown brass, the inner periphery of the liner being eccentric to the outer periphery thereof, interlocking means between the liner and the recess, said crown brass forming entire means whereby the sectional liner is held in the recess and 105 against rotation therein.

In testimony whereof we have signed our names to this specification.

JAMES P. FINERTY.
FRANCIS CROGHAN.
